UNITED STATES PATENT OFFICE.

JOHN A. DE VILBISS, OF ST. LOUIS, MISSOURI, ASSIGNOR TO HENRY L. BOUDREAU, OF ST. LOUIS, MISSOURI.

SPARK-PLUG.

1,246,890.

Specification of Letters Patent. Patented Nov. 20, 1917.

Application filed June 2, 1917. Serial No. 172,436.

To all whom it may concern:

Be it known that I, JOHN A. DE VILBISS, a citizen of the United States, residing at St. Louis, Missouri, have invented a certain 5 new and useful Improvement in Spark-Plugs, of which the following is a full, clear, and exact description, such as will enable others skilled in the art to which it appertains to make and use the same.

10 This invention relates to a spark plug of the type that is provided with a valve for admitting fresh air to the interior of the plug when the plug is in use, so as to prevent carbon from collecting and remaining 15 on the insulator, on the terminals or any other part of the plug in such a way as to cause a short circuit of the electric current supplied to the plug.

One object of my invention is to provide 20 a practicable commercial spark plug of the general type referred to that can be manufactured at a low cost and whose external dimensions are practically the same as the standard spark plugs now in general use.

25 Another object is to provide a spark plug in which one or more gravity seated check valves are mounted in the body portion of the plug in such a manner that they can be retained in operative position either by the 30 insulator or by a member interposed between the insulator and the body portion of the plug. Other objects and desirable features of my invention will be hereinafter pointed out.

35 Figure 1 of the drawings is a vertical sectional view, illustrating a spark plug constructed in accordance with my present invention; and

Fig. 2 is a bottom plan view of the spark 40 plug shown in Fig. 1.

Referring to the drawings, which illustrate the preferred form of my invention, A designates the metal body part of the plug, which is preferably formed from standard 45 bar iron, B designates the insulator and C designates the contact carried by the insulator and projecting downwardly through the cavity or center opening α in the metal body part of the plug. The plug is equipped 50 with one or a plurality of gravity seated check valves which are so arranged that fresh air will be drawn into the center space or cavity α in the metal body part of the plug when the plug is in use, and thus prevent 55 soot from collecting and remaining on

the insulator, on the inner wall of the cavity α , or on the terminals of the plug. The spark plug herein illustrated is provided with two gravity seated ball check valves D, but it is not essential that a plurality of 60 check valves be employed, as a single check valve, properly constructed, will effectively prevent carbon from collecting on the interior of the plug. Each of the check valves D consists of a ball that is mounted in a vertically-disposed bore 1 formed in the metal body part of the plug in close proximity to the center cavity α , said bore being arranged intermediate the ends of an air duct or passageway that leads from the center space or 70 cavity α to the exterior of the metal body part of the plug. One convenient way of constructing the plug is to form the body part from a section of standard bar iron, drill a vertical hole a in the upper end of 75 same, and then counterbore said hole, so as to form the bore 1 in which the ball check valve D is arranged. A horizontally-disposed or inclined hole a' is drilled in the side of the metal body part of the plug adjacent 80 the upper end of same, so as to connect with the hole a , thus forming an air duct or passageway that leads from the lower end of the bore 1 to the exterior of the metal body part of the plug. By constructing the plug 85 in this manner I am able to make the body part in an automatic machine practically in one operation, thus producing the body part at a low cost. The insulator B is provided with a reduced extension b that projects into the center space or cavity α , and the lower end of said insulator is preferably spaced away from the upper end of the metal body part A by means of a gasket or packing element 2, so as to form an air passageway 90 or duct that leads from the upper end of the bore 1 to the cavity α in the metal body part of the plug. It is not essential, however, that the connection between the bore 1 and cavity α be produced in this manner, 95 as said bore and cavity could be connected in various other ways without departing from the spirit of my invention. The insulator B can be combined with the metal body part 100 of the plug in any suitable way without departing from the spirit of my invention, but I prefer to provide the metal body part with a sleeve or annular extension 3 whose upper end portion 3^a is flanged or turned over, so as to engage a gasket or packing element 2^a 105 110

that is mounted on a laterally-projecting flange 4 on the insulator B, thereby permanently connecting the insulator and metal body part together and, forming a gas tight 5 joint between said parts. The gasket 2 not only serves to hold the lower end of the insulator B spaced away from the upper end of the metal body part A, but it also serves as an abutment that limits the upward 10 movement of the check valves D, said gasket being arranged in operative position after the check valves D have been introduced into the bores 1 in the metal body part of the plug.

15 When the engine on which the plug is used is in operation, the check valves D will be unseated when the piston moves in one direction, thereby causing fresh air to be drawn into the center space or cavity α in the metal body part of the plug. When the 20 piston moves in the opposite direction the valves D will seat by gravity, owing to the fact that they are arranged in vertically-disposed bores formed in the body part of 25 the plug. The fresh air that is drawn into the cavity α causes the interior of the plug to be thoroughly scavenged, and said air also prevents soot from collecting and remaining on the insulator, on the contact C, 30 or on the inner wall of the cavity α . Some of the fresh air that enters the cavity α on the suction stroke of the piston remains in said cavity α and becomes trapped in the upper end portion of same on the succeeding 35 compression stroke of the piston, the check valves being arranged close enough to the upper end of said cavity to insure a blanket of compressed air at the base of the extension b on the insulator. When the charge 40 is thereafter exploded at the end of the compression stroke, this trapped air acts as an air cushion which effectively prevents carbon from collecting in the upper portion of the cavity or center space α , either on the exterior of the extension b of the insulator, 45 or on the interior of the portion of the metal body part A that surrounds same.

A spark plug of the construction above described can be manufactured practically 50 as cheaply as spark plugs of the kind now in general use which are not equipped with means for admitting fresh air to the interior of the plug, owing to the fact that the body portion of same is formed from standard bar iron which can be machined in an 55 automatic machine and the check valves are retained in operative position either by the insulator or by the gasket arranged between the insulator and the body part. Another 60 desirable feature of my improved spark plug is that the external dimensions of same are practically the same as the standard spark plugs now in general use, the check valves being completely inclosed in the metal body part of the plug, instead of in

laterally-projecting extensions on the body part. And still another desirable feature of my improved plug is that the passageways through which the air is drawn into the interior of the plug are of such form 70 that the air will flow in a tortuous path, thus tending to prevent a hissing sound.

It is immaterial, so far as my broad idea is concerned, how the terminal or terminals on the metal body part are formed, but I 75 prefer to provide the metal body part A at its lower end with a sleeve or annular extension 5 in which transverse slots 6 are formed, so as to permit one or more of the portions that lie between said slots to be 80 bent inwardly toward the lower end of the contact C, so as to form one or more terminals 7.

Having thus described my invention, what I claim, and desire to secure by Letters Patent, is:

1. A spark plug for internal combustion engines, comprising a symmetrical body part provided with a center space or cavity and with a vertically-disposed bore formed 90 in the upper end of said body part in close proximity to said cavity, said bore communicating with said cavity and with an air inlet passageway in said body part, a ball check valve in said bore, an insulator on said body part that laps over the upper end of said bore, and an extension on said insulator that projects into said cavity.

2. A spark plug for internal combustion engines, comprising a metal body part free 100 from lateral projections and extensions and provided with a center space or cavity, an insulator carried by said body part, a vertically-disposed bore formed in said body part at a point between said cavity and the 105 outer surface of said body part and communicating with said cavity, a ball check valve in said bore, and an air duct or passageway leading from the exterior of the body part to one end of said bore and disposed at right angles to said bore.

3. A spark plug for internal combustion engines, comprising a metal body part provided with a cavity or center space, an insulator having a reduced extension that projects into said cavity, the lower side of said insulator being spaced away from the upper end of said body part so as to form an air duct or passageway, a vertically-disposed bore in said body part which communicates at its upper end with said passageway, a gravity seated ball check valve in said bore, and an air duct in said body part that leads from the lower end of said bore to the exterior of said body part; for 120 the purpose described.

4. A spark plug for internal combustion engines, comprising a metal body part provided with a center space or cavity, an insulator having a reduced extension that pro- 125

jects into said cavity, a vertically-disposed bore formed in the upper end of said body part, a horizontally-disposed air duct leading from the lower end of said bore to the exterior of said body part; a gravity seated ball check valve arranged in said bore, a combined packing and spacing element arranged between the underside of said insulator and the upper end of said body part in 10 such a manner that it serves as an abutment which limits the upward movement of said check valve, and means for connecting said insulator to said body part.

5. A spark plug for internal combustion 15 engines, comprising a metal body part pro-

vided with a center bore or cavity, an insulator provided with a reduced extension that projects into said cavity, a contact on said insulator that projects downwardly through said cavity, a sleeve on the lower end of said body part provided with a portion that is bent inwardly toward said contact so as to form a terminal, a plurality of gravity seated ball check valves arranged in said body part for causing fresh air to be admitted to said cavity intermittently when the plug is in use, and a portion on the upper end of said body part that is flanged over the insulator so as to secure the insulator to said body part. 20 25

JOHN A. DE VILBISS.
